UNITED STATES PATENT OFFICE

2,296,478

PISTON

William F. Morgan, Chicago, Ill.

Application April 9, 1942, Serial No. 438,251

5 Claims. (Cl. 309—15)

This invention relates to new and useful improvements in pistons, and more particularly to pistons used in connection with internal combustion engines.

Thus, it is one of the objects of this invention to provide pistons that are simple in construction, and, therefore, easy and cheap to manufacture.

It is another object of my invention to provide a piston comprising two parts, namely, a head portion and skirt portion.

It is a further object of this invention to provide a piston in two parts with the least amount of contact between the latter, thereby reducing to a minimum the transferring of heat from the head portion to the skirt portion.

It is a still further object of my invention to provide a piston, wherein the two parts, as mentioned, are held together by a wrist pin.

It is an additional object of this invention to provide a plurality of pins to keep the said two piston portions in alignment.

It has also been an object of my invention to provide a design for a piston head, whereby it is possible to construct both parts of the latter of substantially uniform thickness, that is, with all the walls, both of the head and skirt, of practically the same thickness, thereby avoiding the stresses set up in the metal by an uneven heating and expansion.

With the above and other objects in view, this invention consists of the novel features of construction, combination and arrangement of parts, hereinafter fully described, claimed and illustrated in the accompanying drawing, forming part of this specification, and in which similar characters of reference indicate corresponding parts in all views, and in which:

Figure 1 is a vertical section on the line 1—1 of Figure 4.

Figure 2 is a vertical section through a piston ring recess, taken along the line 2—2 of Figure 1.

Figure 3 is a view taken at 90 degrees of Figure 1, half thereof being in section; while

Figure 4 is a bottom plan view of Figure 1.

Referring more particularly to the drawing, 10 designates the piston in general, which consists of the head portion 11, the skirt portion 12, the wrist pin 13, and the aligning pins 14.

The head portion 11 is provided with two lug-like extensions 15, which project into the pockets 16 of the skirt portion 12; the said lug-like extensions 15 are preferably reenforced by ribs 17. The head portion 11 has a plurality of conventional piston grooves 18.

The pockets 16 of the skirt portion 12 each consists of a recessed portion 19 formed by a circular bottom wall 20 and two substantially vertical walls 21 and 22. These walls 20, 21 and 22 form in general appearance a round bottomed U-shaped pocket. The circumference of the skirt portion 12 is also provided with the conventional oil holes 23.

As shown in the drawing, there are spaces S, 10 between the head portion 11 and the skirt portion 12, thus reducing to a minimum the contact of the two parts 11 and 12; and, thus, of course, reducing, also, to a minimum the transfer of the excess amount of heat received by the head portion 11 in the normal course of operation of the internal combustion engine.

The alignment pins 14 consist of an enlarged portion 25 fitting closely into a recess 26 within the bottom portion of the lug-like extensions 15. The bottom portion of the alignment pins 14 is reduced in diameter, as at 27 and fits into an elongated slot 28 in the bottom wall 20. The purpose of this pin is, as previously described, to assist in the alignment of the two major parts. 25 The lug-like extensions 15 are provided with openings 29, while the pockets 16 are provided with openings 30, both openings 29 and 30 providing for a seat of the conventional wrist pin 13.

As illustrated in the drawing, it is considered 30 preferably to provide for the oil holes 23 to terminate, as at 32, in a recessed portion of the outside wall of the skirt portion 12, thereby facilitating the free flow of lubricating oil.

It is obvious that changes may be made in the 35 form, construction and arrangement of the several parts, as shown, within the scope of the appended claims, without departing from the spirit of the invention, and I do not, therefore, wish to limit myself to the exact construction and arrangement shown and described herein.

What I claim as new, and desire to secure by Letters Patent of the United States, is:

I claim:

1. A piston comprising a head portion and a 45 skirt portion, the head portion being formed with lug-like extensions, the skirt portion having pockets adapted to receive the latter, and alignment pins arranged in said lug-like extensions and pockets, substantially as and for the purpose set forth.

2. A piston comprising a head portion and a 50 skirt portion, the head portion being formed with lug-like extensions, re-inforcing ribs integral with the latter, the skirt portion having pockets adapted to seat said lug-like extensions, means

for securing the head portion and the skirt portion together, alignment pins having an enlarged top portion and a reduced bottom portion, the lug-like extensions and the pockets being formed with holes therein of a width to correspond with the width, respectively, of the alignment pins, and adapted to receive the latter.

3. In a device of the class described, a piston comprising a head portion and a skirt portion, the head portion having a plurality of grooves therein, and being formed with two lug-like extensions, the skirt portion having two pockets adapted to seat said lug-like extensions, the latter and the skirt pockets being provided with openings therein, and a wrist pin mounted in said openings, whereby to secure the head portion and skirt portion together, and means for aligning said portions.

4. In a device, as claimed in claim 3, and wherein each of said pockets consists of a recessed portion formed by a circular bottom wall and two substantially vertical walls.

5. A piston comprising a head portion and a skirt portion, said head portion having two lug-like extensions, the skirt portion being formed with two substantially round bottomed U-shaped pockets therein adapted to receive the latter, said head portion and skirt portion being formed with openings therein, a wrist pin mounted in said openings, and means for aligning the head portion and skirt portion, substantially as shown and described.

WILLIAM F. MORGAN.
